UNITED STATES PATENT OFFICE.

WILLIAM B. MARKS, OF WATERBURY, CONNECTICUT.

ELECTRIC TIME SWITCH.

Application filed March 1, 1924. Serial No. 696,135.

To all whom it may concern:

Be it known that I, WILLIAM B. MARKS, a citizen of the United States, and a resident of Waterbury, county of New Haven, 5 and State of Connecticut, have invented certain new and useful Improvements in Electric Time Switches, of which the following is a specification.

This invention relates to electric time switches, and more particularly to a time-switch for automatically shutting off the current from electric lighting systems, electric motors, etc., after any desired predetermined period of use.

One object of this invention is to provide an electric time-switch of the above nature including a central shaft having a radial contact member which is adapted to rotate within the successive layers of a stationary spiral contact member.

A further object is to provide a time-switch of the above nature adapted to be operated by "clock work", the latter being entirely insulated from the path of the electric current.

A further object is to provide a device of the above nature which will be simple, compact, inexpensive to manufacture, easy to manipulate, and very efficient and durable in use.

With these and other objects in view, there have been illustrated on the accompanying drawing two forms in which the invention may be conveniently embodied in practice.

Fig. 1 represents a perspective view of the first form of time-switch as it appears when completely assembled.

Fig. 2 is a diagrammatic view of the wiring circuit of which the electric time-switch forms a part.

Fig. 3 is a perspective view showing the component parts of the switch mechanism in separated relation.

Fig. 4 is a top view of the switch mechanism as it appears when the casing and operating handle have been removed.

Fig. 5 is a top view of a modified form of time-switch also embodying the principles of the invention.

Referring now to the drawings in which like reference numerals denote corresponding parts throughout the several views, the numeral 10 indicates a rectangular support preferably of wood, said support having secured thereto, as by screws, a base 11 of

insulating material preferably formed in the shape of a circular disc. The base 11 is adapted to support a metal framework 12 for housing a suitable clock-work, not shown. The metal framework 12 comprises a pair of rectangular top and bottom plates 13 and 14 connected together at their corners by the usual posts, as clearly shown in Fig. 3.

In order to protect the clock-work and switch mechanism from dust, and to improve the appearance of the device, provision is made of a cylindrical cup-shaped casing 15, said casing being inverted when in use, and having a pair of opposed notches 16 on its bottom edge to receive a pair of conductors 17 and 18. The conductor 17 leads directly to one wire 19 of a source of current, as clearly shown in the diagram of Fig. 2. The conductor 18 leads to a binding post 20 of a lamp socket 21, or to any other electric power consuming unit, such as a bank of lamps, as shown in Fig. 2. A wire 22 leads from the other binding post 23 of the lamp socket 21 or other unit to the second wire 24 of the source of current.

The top of the casing 15 is provided with a dial 25, having a scale graduated in any suitable manner, as into minutes as shown. An operating arm 26 and a pointer 27 are mounted to rotate above said dial 25. The arm 26 is provided with a knob 28 at its outer end by means of which the pointer, which is rigidly connected at any desired angle to the arm 26, may be rotated to set the pointer at any position upon the dial.

The arm 26 and the pointer 27 are detachably secured on the end of a hollow collar member 29 by means of a screw 30 threaded into the top of said collar member. The collar member 29 is adapted to extend down through a central aperture 30a in the top of the casing 25, and is provided at its lower end 31 with a tapped hole 31 adapted to screw upon the upper threaded portion 32 of a central main shaft 33 mounted in suitable bearings in the upper and lower plates 13 and 14, previously mentioned. The central shaft 33 is adapted to be driven by a suitable spring motor and gearing not shown, and the gearing is preferably so arranged that the pointer 27 will make one revolution per hour.

Rigidly mounted on the central shaft 33

above the plate 13 is a stationary flat insulating ring 34, said ring 34 being secured to the plate 13 in any suitable manner, as by screws adapted to fit in screw holes 35. 5 The ring 34 is provided with a large aperture at its center and has a radial slot 36 extending from its outer perimeter part way to the central aperture thereof. As clearly shown in Figs. 3 and 4, one side of the 10 slot 36 is cut off square while the other side is tapered to form a wedge portion 37, for a purpose to be hereinafter described.

In order to provide a stationary electrical 15 contact, a narrow metallic ring 38 is provided flush with the inner circumference of the aperture in the insulating ring 34, said metallic ring being secured to said insulating ring by means of rivets 39. The 20 metallic ring 38 has a downwardly extending section 40 at one side to which is connected an elbow member 41 having a depending binding terminal 42 located outside of the clock framework inside of the 25 casing 15. The terminal 42 is adapted to be connected to the conductor 17 previously mentioned, as by a binding screw 43.

A movable metallic contact ring-member 44 is located on the central shaft 33 above 30 the stationary metallic ring 38, said movable ring-member 44 being connected, as by rivets 45 to a disc 46 of insulating material. The disc 46 in turn is adapted to be secured at its center to a circular plate 47, as by 35 rivets 48, said plate 47 surrounding the central shaft 33 and being seated on a shoulder formed at the bottom of the threaded section 32. A washer 49 is preferably located immediately above said plate 47. The movable 40 contact ring 44 is provided on one side with a short arm or lug 50 adapted to lie in electrical contact with the stationary ring 38 at all times. The movable contact ring 44 is also provided at a point directly opposite 45 the lug 50, with a resilient long arm 51 having a raised section 52, which is arched upwardly to bridge over the stationary contact ring 38 so as to avoid a short circuit. The outer extremity of the 50 long arm 51 lies in the plane of the ring 44 and is adapted to press down upon and electrically engage between the layers of a spiral coil 53.

The spiral coil 53 which is made of flat 55 strip metal, may have any desired number of turns according to the length of time the lamp or other power-consuming device is to be used. Normally, the faces of adjacent sections of the coil 53 are adapted to lie in 60 flat contact with one another. The upper extremity 54 of the spiral coil 53 is free, while the lower end thereof is bent reversely upon itself at 55 around the wedge portion 37 of the insulating disc 34 upon 65 which the spiral coil rests. The lower end

of the spiral coil 53 is provided with a depending lug 56 located outside the framework of the clock, and being spaced about 45 degrees from the binding terminal 42. The lug 56 is adapted to be connected by 70 means of a binding screw 57 to the conducting wire 18, previously mentioned.

Directly above its reversely bent lower end 75 53, the spiral coil 53 is provided with a flat horizontal bent-over portion 57^a, which is 80 adapted to lie in the plane of the lower stretch of the coil. By means of this construction, when the clock is unwinding, the outer extremity of the long arm 51 of the 85 movable ring 44 will gradually pass downwardly between the successive layers of the coil 53, and will then ride horizontally upon the flat section 57^a until it reaches its edge, whereupon it will suddenly drop into the slot 36, by reason of its resiliency, instantly 90 shutting off the flow of current.

While the adjacent layers of the spiral coil are shown separated in Fig. 3, for clearness, it will be understood that said layers will normally lie in contact substantially 95 throughout the entire length of the coil.

In operation, when it is desired to set the time-switch to operate in a period of time less than one hour, the handle 26 will be rotated so as to move the pointer 27 around the dial in a clockwise direction until the pointer is opposite the proper scale-reading which in this case will be something less than 60 minutes. When, however, the period of time is greater than one hour, the operator will rotate the handle 26 in a clockwise direction, one revolution for each hour, and will then continue to rotate the pointer an additional distance, as described above, to take care of the additional minutes.

One advantage of this invention lies in the fact that the shaft for operating the time-switch is not limited to a single revolution as was the case with former time-switches, but may make a plurality of revolutions,—the number depending on the number of turns in the spiral coil.

By means of this construction, it results that the present time-switch may be very accurately adjusted, even down to a fraction 115 of a minute, whereas former types of time-switches could only be roughly adjusted to fractions of an hour.

In the operation of the present invention, when it is desired to set the time-switch, 120 the handle 26 will be turned in a clockwise direction to the desired point, as already described. During this operation, the extremity of the long arm 51 will ride over the curved cam surface of the lower end 125 of the coil 53 under the flat portion 57^a. During the unwinding, the clock-work mechanism will cause the shaft 33 and its associated long arm 51 and pointer 27 to rotate in a counter-clockwise direction until 130

the long arm 51 has again opened the circuit in the manner described above.

In some cases, it may be desired to shut off the power before the time for which the time-switch has been set. For this purpose, the modified form of device shown in Fig. 5 may be employed. This form of time-switch is similar to that shown in Fig. 2, but the terminal 42 of the stationary contact ring 38 has a horizontal portion 58 which extends out radially through a slot in the casing 15. The portion 58 forms one terminal of a manually-operated switch, which is operated by a bell crank lever 59 pivoted upon a pin 62 located on a metallic strip 60, secured to the support 10. The strip 60 has a screw 61 at its outer end to serve as a binding post for the conducting wire 17. The lever 59 is provided with a knob 63 at its outer end so that it may be manipulated to swing the lever about its axis when it is desired to open the circuit independently of the time-switch mechanism.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an electric time-switch, a clockwork mechanism, a stationary contact disc forming one terminal of said switch, a coiled strip of metal having overlapping layers, said strip being insulated from said stationary contact disc and forming the other terminal of said switch, a rotary metallic member connecting said disc and said strip and capable of rotating in contact with said strip for more than 360 degrees, said connecting member being driven by said clockwork, and the circuit being broken when said connecting member passes beyond the end of said strip.

2. In an electric time-switch, a stationary contact disc electrically connected to one terminal of a source of current, a spiral strip concentric with said disc and connected to a power consuming device said strip having a plurality of overlapping layers, a motor-driven metallic connecting member having a lug in contact with said disc, said connecting member having an arm adapted to successively pass over the layers of said strip, said circuit being broken when the arm of said connecting member passes over the extremity of said strip.

3. In an electric time-switch, a stationary contact disc electrically connected to one terminal of a source of current, a coiled strip having overlapping layers, said strip being concentric with said disc and connected to a power consuming device, a motor-driven connecting member having a lug on one side in contact with said disc, said connecting member having an arm opposite said lug lying in contact with said strip, said circuit being broken when the arm of said connecting member passes over the extremity of said strip.

4. In an electric time switch, a stationary contact disc electrically connected to one terminal of a source of current, a spiral strip concentric with said disc and connected to a power consuming device, a motor-driven connecting member having a lug in contact with said disc, said connecting member being pivoted on an axis within said disc, having an arm bridged over said disc and adapted to pass between two adjacent layers of said strip, said circuit being broken when the arm of said connecting member passes over the extremity of said strip.

5. In an electric time-switch, a clockwork frame, a stationary metallic disc secured to said frame and insulated therefrom, said disc forming one terminal of the switch, a helical strip having more than one turn surrounding said disc and forming the other terminal of the switch, a main shaft driven by said clockwork, a connecting member mounted on said main shaft and insulated therefrom, said connecting member electrically engaging said disc and said strip, said switch being automatically opened by said clockwork when said connecting member becomes disengaged with the end of said frame.

6. In an electric time-switch, a clockwork mechanism, a stationary contact disc forming one terminal of said switch, a spiral strip having a total angle of greater than 360 degrees insulated from said stationary contact disc and forming the other terminal of said switch, a rotary member connecting said disc and said strip, said connecting member being driven by said clockwork, the circuit being broken when said connecting member passes beyond the end of said spiral strip, a casing having a dial enclosing said mechanism, and a setting and indicating handle located above said dial outside said casing the switch being capable of being set so as to cause said handle to rotate around said dial more than 360 degrees.

7. In an electric time-switch, a clockwork mechanism a stationary contact disc forming one terminal of said switch, a spiral strip insulated from said station contact disc and forming the other terminal of said switch, a rotary member connecting said disc

- and said strip, said connecting member being driven by said clockwork, the circuit being broken when said connecting member passes beyond the end of said spiral strip,
- 5 a casing having a dial enclosing said mechanism, and a setting and indicating handle located above said dial outside said casing, said handle being mounted to rotate with said rotary member.
- 10 8. In an electric time-switch, a clockwork mechanism, a stationary contact disc forming one terminal of said switch, a spiral strip having overlapping sections insulated from said stationary contact disc and forming the other terminal of said switch, a rotary member connecting said disc and said strip, said connecting member being driven by said clockwork, the circuit being broken when said connecting member passes beyond
- 15 the end of said spiral strip, a casing having a dial enclosing said mechanism, a setting and indicating handle located above said dial outside said casing.
- 20 9. In an electric time-switch, a support, a base on said support, a clockwork frame 25 on said base, an insulating ring secured to the top of said frame, a terminal at the center of said ring, a helical strip terminal at the periphery of said ring, said ring having a slot in its edge, one end of said slot being curved to form a cam or wedge, said clockwork having a main shaft at the center of said ring, and a connecting member on said shaft adapted to electrically engage said terminal and said strip.
10. In an electric time switch, a rotary contact member, a motor for driving said rotary member, a stationary contact member consisting of a helical metal strip having overlapping layers, whereby the switch may be set to cause the rotary member to traverse more than one turn of said strip, and means to cause the circuit through said switch to open when the rotary member passes beyond one end of said strip.
- In testimony whereof, I have affixed my signature to this specification.

WILLIAM B. MARKS.
